US0D1016804S

(12) **United States Design Patent** (10) **Patent No.:** **US D1,016,804 S**
(45) **Date of Patent:** **** Mar. 5, 2024**

(54) **NOTEBOOK COMPUTER**

(71) Applicant: **Acer Incorporated**, New Taipei (TW)

(72) Inventors: **Yun-Ju Chou**, New Taipei (TW);
Pao-Ching Huang, New Taipei (TW)

(73) Assignee: **Acer Incorporated**, New Taipei (TW)

(**) Term: **15 Years**

(21) Appl. No.: **29/826,019**

(22) Filed: **Feb. 8, 2022**

(30) **Foreign Application Priority Data**

Oct. 29, 2021 (TW) 110305853

(51) **LOC (14) Cl.** **14-02**

(52) **U.S. Cl.**

USPC **D14/318**

(58) **Field of Classification Search**

USPC D14/300, 315–327, 333–335, 338–340;
D18/1–2, 7, 11, 12.2, 12.3
CPC G06F 1/1616; G06F 1/1637; G06F 1/1662;
G06F 1/1686

See application file for complete search history.

(57) **CLAIM**

The ornamental design for a notebook computer, as shown and described.

DESCRIPTION

FIG. 1 is a perspective view of a notebook computer showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of the indicated portion 9 in FIG. 1;

FIG. 10 is a perspective view thereof showing the notebook computer in the usage status;

FIG. 11 is another perspective view thereof showing the notebook computer in the usage status;

FIG. 12 is a perspective view thereof showing the notebook computer in another usage status; and,

FIG. 13 is another perspective view thereof showing the notebook computer in another usage status.

The dashed broken lines illustrate portions of the notebook computer that form no part of the claimed design. The dot-dash broken line indicates cutoff boundaries for enlarged detail portion views and form no part of the claim.

1 Claim, 13 Drawing Sheets
